UNITED STATES PATENT OFFICE

CHARLES E. FRIESNER, OF TOLEDO, OHIO, ASSIGNOR TO THE HETTRICK MANUFACTURING COMPANY, OF TOLEDO, OHIO, A CORPORATION OF OHIO

COUCH HAMMOCK

Application filed May 15, 1931. Serial No. 537,525.

This invention relates to articles of furniture, but more particularly to couch hammocks commonly known as gliders, which are provided with a swinging seat suspended 5 from the supporting frame, and an object is to improve the suspension of the seat in such manner as to permit to and fro swinging movements, but effectively resist undue side swing by means which are simple and inexpensive, and which preferably are detachable to enable the seat to be detached from its support for purposes of shipment and storage.

Other objects of the invention will hereinafter appear, and, for purposes of illustration, but not of limitation, an embodiment of the invention is shown on the accompanying drawings, in which:

Figure 1 is a perspective view of a couch 20 hammock equipped with my novel means for suspending the swinging seat from the supporting frame;

Figure 2 is an enlarged perspective view 25 of one of the hanger member parts to which it is connected;

Figure 3 is a fragmentary view of a corner of the seat showing an alternate leg portion for receiving a hanger member;

Figure 4 is a diagrammatic view of the 30 lever hanger for the seat and associated parts;

Figure 5 is a view similar to Fig. 2 of an alternate form of hanger; and

Figure 6 is a view of another alternate 35 form in which the hanger is connected to the adjacent leg.

The illustrated embodiment of the invention comprises a couch hammock or glider having a seat 10, a back 11 and supporting frame generally designated by the reference character 12. More specifically, the supporting frame comprises two end frame members 13 and 14, which are connected adjacent their lower portions to horizontal brace members 15. The side frames 13 and 14 each comprises two angle iron uprights 16, the lower ends of which are riveted to a foot 17, which is adapted to rest at its outer ends on a suitable supporting surface. It will be 50 observed that the intermediate portion of the

foot member is bent upwardly a short distance from the ends to provide a central portion spaced from the supporting surface, this being found desirable to prevent the glider from tipping under undue swinging movements.

Brace members 18 and 19 connected respectively to the foot 17 and upright 16 serve to provide a rigid structure. Extending across the upper end of the uprights 16 is a rail 20 having a depending flange 21. The rail 20 is riveted to the uprights 16 and is held rigid by braces 22. It will be observed that the rail 20 is disposed above the seat 10 and projects beyond the sides of the uprights 16.

The seat 10 and back 11 may be provided with suitable upholstery 23. The seat 10 is formed of end members 24 and side members 25. A suitable seat spring (not shown) may be held in the frame in any suitable manner. At each corner of the seat frame is a leg 26 in this instance of angle iron, which depends from the seat frame a relatively short distance and adjacent the lower end of the leg 26 is an opening 27. Instead of the opening 27 a notch 38 may be employed, as shown in Fig. 2.

The seat 10 is suspended from the top rails 20 in such manner as to permit forward and rearward swinging movements similar to the motion of a seat suspended from a point a considerable distance above the glider. However, the suspension is such as effectively to overcome or resist any endwise movement of the seat to return it to its normal position centrally located between the two side frame members so that during swinging the seat will follow a substantially straight back and forth path of movement, and will not hit against the end frame members. The suspension of the seat is such also to prevent any side sway due to unbalanced positioning of the load, and to maintain it in normal position laterally with respect to the supporting frame regardless of the positioning of the load thereon.

As shown, each corner of the seat frame is suspended from the adjacent top rail 20 by an open link or hook 28, which engages

through an opening 29 in the depending flange 21 of the top rail. The lower end of the link 28 hooks through an opening 30 in a hanger 31, which is rigid, or substantially so, and, in this instance, consists of a metal rod or lever having a downwardly extending portion 32, which inclines slightly toward the leg 26, an inwardly extending portion 33, which projects through the opening 27 in the 10 leg (the opening 27 being slightly larger than the lever 31 to permit rocking movements of the seat with respect to the hanger) and an upwardly inclined portion 34. An open link 35 hooks through an opening 36 in the inner 15 end of the lever, and the opposite end of the link hooks through an opening 37 in the side rail 25 at a point spaced from the leg 26. Although the lever is shown round it may be flat, if desired and may be of materials 20 other than metal.

From the above description it will be apparent that the hangers or levers 31 effectively resist endwise movement of the seat relatively to the frame supports 13 and 14. Referring particularly to Fig. 2, movement of the seat endwise or toward the frame portion is prevented by the hangers 31 because any force imparted to the seat 10 tending to move it to the right of Fig. 2, will tend to 25 rock the hanger or lever 31 about its fulcrum or where it contacts with the apertured portion of the leg 26, in a counter clockwise direction. Since the inner end of the lever is anchored to the seat 10 through the link 35 30 rocking movement of the lever 31 is effectively resisted. This is clearly shown diagrammatically in Fig. 4.

It is important that the lever or hanger 31 extend through the apertured portion in the 40 leg 26 underneath the seat 10 a sufficient distance to obtain the desired leverage, but, as shown in Fig. 5, it is not essential that the lever extend up to the rail 25 of the seat, but it may terminate short of this member and be 45 connected thereto by a chain or other suitable connection 39. Furthermore, the lever 31 may be suitably connected as by a link 40 to the inner side of the leg 26, as shown in Fig. 6.

50 It is to be understood that numerous changes in details of construction and arrangement may be effected without departing from the spirit of the invention as defined in the appended claims.

55 What I claim as new and desire to secure by Letters Patent is:

1. In combination with a frame having spaced ends, a seat disposed in the space between the frame ends, a leg depending from 60 each corner of the seat and having an aperture, and a hanger for each leg including a substantially rigid lever having one arm pivoted to the frame on one of said ends and 65 having a second arm disposed at an angle to the horizontal and extending loosely through

the leg aperture whereby the latter affords a fulcrum for the lever, and a swinging connection between the second arm of each lever and the seat whereby to prevent substantial downward movement of the lever relative to the seat so as to resist endwise movement of the seat while permitting forward and rearward swinging thereof.

2. In combination with a frame having spaced ends, a seat disposed in the space between the frame ends, a plurality of independent suspension elements having rigid portions and located at the respective corners of the seat, means to connect the upper end portions of said suspension elements to the frame, means depending from the seat adapted to receive a rigid portion of each suspension element and providing a fulcrum therefor, and swinging connections between the lower end portions of said suspension elements and the seat adapted to prevent substantial downward movement of the suspension elements relative to the seat thereby to resist endwise movement of the seat but enable forward and rearward swinging movement thereof.

3. In combination with a frame having spaced ends, a seat disposed in the space between the frame ends, a hanger for each corner of the seat including a substantially rigid lever having one arm pivoted to the frame, and having a second arm disposed at an angle to the horizontal, fulcrum means for each of the hangers carried by the seat and engaged with the lever thereof whereby the latter affords a fulcrum for the lever, and a 95 swinging connection between the second arm of each lever and the seat whereby to prevent substantial downward movement of the lever relative to the seat so as to resist endwise movement of the seat while permitting forward and rearward swinging thereof.

In testimony whereof I have hereunto signed my name to this specification.

CHARLES E. FRIESNER.
